US00D960629S

(12) **United States Design Patent** (10) Patent No.: **US D960,629 S**
Huang et al. (45) Date of Patent: **** Aug. 16, 2022**

(54) **COOKING APPLIANCE**

- (71) Applicant: **WHIRLPOOL CORPORATION**, Benton Harbor, MI (US)
- (72) Inventors: **XinFeng Huang**, Shenzhen (CN); **Yu Liu**, St. Joseph, MI (US); **Kyle A. Walters**, Benton Harbor, MI (US); **XunCai Zhang**, Shenzhen (CN); **Bin Huang**, Shenzhen (CN)
- (73) Assignee: **Whirlpool Corporation**, Benton Harbor, MI (US)
- (**) Term: **15 Years**
- (21) Appl. No.: **29/797,591**
- (22) Filed: **Jul. 1, 2021**

Related U.S. Application Data

- (63) Continuation of application No. 29/695,608, filed on Jun. 20, 2019, now Pat. No. Des. 927,241.

CLAIM

The ornamental design for a cooking appliance, as shown and described.

DESCRIPTION

FIG. 1 is a front perspective view of a cooking appliance according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part of the claimed design.

The broken away symbols in the drawings indicate that any portions of the article beyond what is shown forms no part of the claimed design.

1 Claim, 6 Drawing Sheets(56)
